METHOD OF DELINEATING OR REPRODUCING PICTURES AND DESIGNS.

1,254,764.

Specification of Letters Patent. Patented Jan. 29, 1918.

Application filed December 1, 1915. Serial No. 64,441.

To all whom it may concern:

Be it known that we, ROY C. BECK, EDWARD A. OWENS, and JACOB H. STEINMAN, citizens of the United States, residing in the city and county of San Francisco and State of California, have invented new and useful Improvements in Methods of Delineating or Reproducing Pictures and Designs, of which the following is a specification.

This invention relates to a method of delineating or reproducing pictures and designs.

The object of the present invention is to provide a method whereby a picture or design containing one or more colors may be delineated or reproduced on smooth, semi-smooth or rough surfaces, such as paper, cardboard, linoleum, leather, fabrics, wood, glass, metal, etc., without the use of engraved plates of any kind. Further objects will hereinafter appear.

The method will hereinafter be more fully described and claimed, having reference to the accompanying drawings, in which—

Figure 1 is a view of the original sketch to be reproduced.

Fig. 2 represents a card of green color upon which card the multi-colored sketch of Fig. 1 is to be reproduced by our process.

Fig. 3 is a view of the card shown in Fig. 2, after the blue color has been applied.

Fig. 4 shows the same card with the brown color applied.

Fig. 5 represents the next step with the white color applied.

Fig. 6 represents the next step with the yellow color added.

Fig. 7 represents the same card after the last color, which is red, has been applied, and the reproducing operation completed.

Fig. 8 is a perspective view of the stencil frame through which the colors are applied.

Referring to the drawings in detail, the operation of the process will be as follows:

The sketch or drawing to be reproduced is represented in Fig. 1, and indicates a landscape in multi-chrome. The colors which are diagrammatically represented are green, indicated at 4; blue indicated at 5; brown indicated at 6; white indicated at 7; yellow indicated at 8, and red indicated at 9.

Fig. 1 will be referred to, for convenience, as the "master pattern". Fig. 2 is the card or other surface upon which the scene of

Fig. 1 with its respective colors is to be 55 reproduced.

2 is an open-mesh screen, consisting of copper or brass-gauze, bolting cloth or other suitable material, tightly stretched on a rigid wooden or metal frame 3; this screen 60 and frame being of such size as to be superimposed on the sketch to be reproduced.

In Fig. 2 the card on which the reproduction is to be made is represented as having a green surface, the color having been 65 applied in any appropriate manner, green in this instance being the background color.

The first color to be applied on this background of green, is blue, indicated at 5, and here begins practically the first step of 70 our process.

Step 1—Tracing and blocking.—The tightly stretched screen 2 is laid upon the master pattern of Fig. 1, and the outline of all that portion or portions of the master 75 pattern shown in green, and which green tones are to be preserved in the reproduction, are carefully traced on the screen; these traced portions then being painted over with shellac, varnish, glue, asphalt, or 80 any other suitable material. This is termed "blocking out." In other words, the meshes of the screen inclosed by the traced outline indicative of green are closed by a suitable filler or impermeable mask to prevent any 85 paint or coloring matter going through. The effect of such protection is to protect the base or background color, on the card of Fig. 2, (in this instance indicated as green at 4,) to prevent any of the succeeding 90 colors from over-laying it, thus permitting the original color, green, to appear through all the successive color runs. The meshes may also be closed by suitable masks or stencils cut from paper, tissue, metal or 95 any material best suited for the work in hand.

Step 2—Applying the color.—When a color is to be applied, it is only necessary to place the card below the screen or stencil 100 frame as previously described in such a manner that a perfect register is always obtained. The frame is preferably hinged to a flat surface adapted to receive the card and any suitable means may be provided for 105 securing a perfect register between the card and the frame when the tracing is being made and during each succeeding run.

The color may be applied in any suitable manner, but is preferably poured on to the screen surface and forced through the meshes, that are not blocked out, by passing 5 a flexible scraper, commonly known as a squeegee, or roller over the surface of the screen. The color applied is thus forced evenly through the open meshes of the screen and will adhere to the surface of 10 the card and cover the parts desired. The use of a squeegee or roller for forcing the color under comparatively high pressure through the screen makes possible the use of a color of such high viscosity that there 15 is no danger of its underrunning the edges of the pattern and blurring the margin lines.

The run of the blue color 5 covers, as indicated at Fig. 3, all that part of the 20 surface on which the reproduction is made, except the previously traced and blocked out or permanently masked green portions 4.

Step 3—Washing so as not to affect the blocking.—After the first color blue, indicated at 5, Fig. 3, has been applied to all 25 the cards, it is necessary to change the stencil to permit the application of the next color. This is accomplished by thoroughly washing the stencil frame, that is screen, 2, 30 to remove all the composition or paint by any suitable solvent which will not affect or remove the shellac or other protective material used in masking that portion of the screen protecting the green areas 4. In 35 other words, these masks of a previous run remain on the screen throughout the operation, and as we will see the entire screen, except the area for the very last color applied, is eventually blocked out. Having 40 washed out the blue paint we then have a clear screen for all those portions except which are permanently masked by the green areas indicated at 4, Fig. 3.

Step 4—Tracing the next color and blocking.—The screen stencil is laid again on the 45 master pattern of Fig. 1, and a tracing made on the screen wherever the blue color appears. All parts of the screen where the blue of Fig. 1 is to be retained, are then 50 coated or masked, as previously described in connection with color 4. That is to say, all the area or areas in blue appearing on Fig. 1, are blocked-out on the screen, in this manner permitting the next color which 55 is shown as brown, 6, to pass through only that part of the screen not protected for the green and blue of the original or master pattern. All areas except the underlying green are allowed to receive a deposit of 60 paint so that a building-up or embossing effect is eventually produced.

Step 5—Applying the next color.—The traced screen, now having the colors 4—5 of the master pattern blocked out, is placed on 65 the card of Fig. 3, and brown paint is then

poured on to the screen surface and forced through the still open meshes by a squeegee action, as before, producing a card such as shown in Fig. 4, with its three colors, green, blue and brown (4—5— and 6).

Step 6.—The screen is then washed as before, so as not to disturb the masks for the green and blue.

Step 7.—The screen is next placed over the master pattern and the brown areas 6, 75 showing through the screen, traced and then blocked out.

Step 8—Applying the next color.—The white color 7 is then applied through the remaining open meshes of the screen by 80 squeegee action, as previously described in steps 2 and 5.

Step 9.—The white is then washed off the screen so as not to disturb the masks for the green, blue and brown.

Step 10.—The white of the master pattern is traced and blocked, similarly as in steps 1—4 and 7.

The card has now four colors upon it, green, blue, brown and white, 4—5—6 and 7. 90

The yellow color, indicated at 8, is next run through in the same manner as the other colors, and finally the red color, indicated at 9, is run.

Any number of colors may be applied in 95 this manner after masking out after each successive run whatever part of the last color run is to be maintained; the same operation being repeated until all colors in the original drawing have been run. The finished print will then appear as an exact facsimile of the original sketch.

By referring to the several Figs. 2, 3, 4, 5, 6 and 7 which show the step by step application of each individual color, it will be seen 100 that each color partly overlays the other; in other words, the several colors are superposed in distinct layers one on top of the other. This is of great importance as it not only permits a natural modeling and embossing of all designs but also a clean cut margin line and perfect register of all colors.

From the foregoing, it is seen that the different steps follow each other in cycles, each color constituting a different cycle, and 110 each cycle differing from the other cycles in respect to the areas treated. A cycle in short consists of:

- (1) Securing a suitable background color;
- (2) Tracing upon a tightly stretched screen from a master pattern, the background color to be preserved;
- (3) Blocking the traced area on the screen;

(4) Laying the screen in close contact with the surface to be treated, and in proper register therewith;

- (5) Applying a thickish paint on to the screen;

(6) Forcing the paint by even pressure through the screen with a squeegee or equivalent, and maintaining the screen in close contact all the time with the surface to be treated;

(7) Removing the screen and washing off the paint, but not disturbing the already blocked areas on the screen;

(8) Tracing and blocking the colored 10 areas on the screen from the master pattern, which areas correspond with the color just applied thus producing an embossed effect of considerable thickness, and in as many colors as there are layers of color.

15 The stencil form can be made also by sensitizing either metal, silk or other fabric of an open mesh nature and printing on same photographically, fixing the image so obtained and depositing solid matter chemi-

20 cally on such image and electroplating same; also by painting the image with any composition which can be electroplated and plating same with any suitable metal. The method of reproducing pictures described in

25 the foregoing specification may also be applied when necessary in the form of a separate stencil for each color, constructed as heretofore described and so arranged that each will register in its proper place, to register with preceding colors. Both plans are part of this method. (This method permits reproduction on paper, cardboard, wood, leather, textiles, gauze, fine mesh screens, glass, porcelain, celluloid or any other suitable materials; also on rough surfaces, such as emery cloth, fine gravel roofing, asbestos or any material having a rough surface, where ordinary methods are useless.

30 The size of the work can be from a post card size to a bill board strip approximately three feet wide to ten feet high. Each section of a bill board can be made so that when they are pasted side by side, a complete picture is made.

45 The present process entirely eliminates any sort of engraving of plates, such as wood cuts, zinc, copper or the like, thereby eliminating the expensive method of reproducing color work or designs by costly engraving. The method furthermore permits the use of oil colors, and this is desirable as it gives a distinctive effect not possible with the usual method of printing. Water colors or any other suitable semi-plastic material 55 may also be used for embossed effects.

The present method permits the colors to be overlaid and therefore, permits the production of raised effects not possible by ordinary methods of printing.

60 Having thus described our invention, what we claim and desire to secure by Letters Patent is—

1. A method of producing multi-colored pictures or designs which comprises successively forcing a plurality of colors through

a single screen which is partly blocked out after each color run in such a way that at least a part of a succeeding color will extend over part of a preceding color.

2. A method of reproducing multi-colored pictures from a master pattern, which comprehends the application on a suitably colored background of a card or other surface to be treated, successive colors making up the picture to be copied through the medium 75 of a screen by tracing on the screen the area or areas on the master pattern corresponding to the color of the aforesaid background, blocking said area or areas, laying the screen upon the said surface to be treated, applying a coloring medium through the open meshes of the screen by squeegee action, washing out the paint from the screen without affecting the previously blocked areas, re-tracing on the screen from the master 80 pattern the colored areas in the master pattern corresponding to the color just run, blocking out on the screen these traced areas, applying a succeeding color and repeating the cycle of operations until all the colors in 85 the master pattern have been reproduced upon the said surface to be treated.

3. A method of producing multi-colored pictures or designs having embossed portions which comprises successively forcing 95 a plurality of comparatively thick colors through a single screen which is partly blocked out after each color run in such a way that one or more succeeding colors will at least partly overlay a preceding color. 100

4. A method of producing multi-colored pictures or designs which comprises successively forcing a plurality of colors through a single partly blocked out screen which is differently reblocked after each color run in 105 such a way that at least part of a succeeding color will extend over part of a preceding color.

5. A method of producing multi-colored pictures or designs which comprises successively forcing a plurality of colors through 110 a single screen which is partly blocked out after each color run in such a way that at least a part of each succeeding color will extend over a part of the immediately preceding color.

6. A method of producing multi-colored pictures or designs which comprises successively forcing a plurality of colors through 120 a single screen which is partly blocked out after each color run in such a way that a succeeding color will be superposed upon a preceding color.

7. A method of producing multi-colored pictures or designs which comprises successively forcing a plurality of colors through 125 a single screen which is partly blocked out after each color run in such a way that a succeeding color will be superposed upon superposed preceding colors. 130

8. The method of reproducing multi-colored pictures through the medium of a screen and a master pattern, which comprises as a step or cycle therein tracing on the screen 5 from the master pattern the area or areas of a single color, blocking those areas on the screen, applying the screen to a surface to be treated upon which there has already been applied a color corresponding to the areas 10 blocked out, running color through the remaining open meshes of the screen, removing the screen and washing from it the color just run without disturbing the previous blocking on the screen, then laying the 15 screen over the master pattern and tracing thereon the area or areas corresponding to the color just run, blocking these traced areas, placing the screen again on the surface to be treated, applying color through 20 the open meshes of the screen, washing the screen and repeating the cycle of tracing, blocking, running the color, and washing until all the colors have been reproduced.
9. A method of producing multi-colored 25 pictures or designs having embossed portions and clean cut margin lines which consists in tracing on a screen covered frame from an original which it is desired to reproduce, the outline of a color which it is 30 desired to first apply, blocking out all the surface exterior of the traced lines by filling in with shellac or other material, then placing the screen on the surface upon which the color is to be applied, depositing paint 35 thereon and forcing it through the open meshes of the screen by running a flexible scraper over the screen, again tracing on said screen an outline for a second color and blocking out the remaining surface to cause the second color, when forced through the 40 screen, to partly overlay the first, then proceeding with each individual color until all are applied.
10. A method of reproducing multicolored pictures which comprehends the application 45 of successive colors making up the picture to be reproduced upon a surface to be treated, through the medium of a tightly stretched screen maintained in close contact with the surface to be treated while a particular color 50 is being applied by means of a squeegee, each color being applied through a partly different portion of the screen from that through which any other color is applied, and blocking out on the screen each successive color 55 area after the preceding color has been applied through the screen so as to render a part of the previously permeable portion of the screen impermeable to the succeeding color runs.
- In testimony whereof we have hereunto set our hands in the presence of two subscribing witnesses.
